CLAIM

The ornamental design for combination book enclosure
and reading lamp, substantially as shown.

DESCRIPTION

FIG. 1 is an isometric view of a combination book enclosure and reading lamp showing my new design;
FIG. 2 is a bottom plan view;
FIG. 3 is a front elevational view;
FIG. 4 is an elevational view showing one side;
FIG. 5 is an elevational view showing the side opposite
the one side of FIG. 4;
FIG. 6 is a top plan view; and
FIG. 7 is a rear elevational view thereof.
